ration of Vermont

Application February 9, 1932, Serial No. 591,829

26 Claims. (Cl. 26—17)

This invention relates to automatically controlled cloth shearing machines and is intended to provide controlling means for a cloth shear that will be thoroughly reliable in action by eliminating danger of damage to the cloth through imperfect operation of the control mechanism and at the same time shall permit rapid travel of the cloth through the machine with the shearing action interrupted only for a brief period sufficient to allow the cloth seam or sewing to pass between the shear blades and the cloth support, these elements being promptly closed after the seam has passed through.

As those skilled in the art know, it is customary when shearing or cropping the face or faces of pieces of cloth to sew a considerable number of these pieces end to end in order to avoid threading each individual piece into the machine separately. While this practice shortens the time of cropping a given number of pieces of cloth, nevertheless it makes necessary the provision of means for opening apart the shear blades and the cloth supporting rest which constitute the shearing couple. The opening and closing of the elements of each shearing couple, in case it is a multiple shear, by automatic mechanism energized by the seam approaching the shearing line as heretofore practiced, has been subject to much adverse criticism, since failure of the apparatus to function properly has often resulted in allowing slubs or knots on the face of the cloth to operate the automatic mechanism, which in many cases would act to close the shearing couple just at the time that the transverse seam or sewing is closely approaching the shearing line, so that the cloth is badly cut at the seam and in the case of a multiple machine may be very badly damaged.

It is the object of the present invention to eliminate this trouble in cloth shearing machines by providing a mechanism operating on a principle that will result either in preventing slubs, knots and excrescences on the face of the cloth from energizing the automatic seam-controlled mechanism, or that, in the possible but remote contingency, the automatic control mechanism shall be set in action by individual slubs or knots, the shearing couple or couples will be kept open to permit the near approaching seam that follows from being cut or damaged by the return or closing movement of the shearing elements. Another feature of the invention consists in providing means by which the timing between the opening and the closing of the shearing elements may be so adjusted as to permit the immediate

closing of the shearing elements after the seam has passed the shearing line. Provision is also made against the cloth becoming jammed in the feeler mechanism which energizes the means for opening the shearing elements. These and other features of the present invention will be described in the following specification and will be defined in the claims hereto annexed.

In the accompanying drawings we have illustrated a construction and arrangement operatively embodying the various features characterizing the present invention, in which

Fig. 1 is a right hand side elevation of so much of a cloth shearing machine as may be necessary to understand the application of the present improvement to a cloth shear, a considerable part of the frame work and other mechanism being omitted to permit clearer illustration of the present invention.

Fig. 2 is a similar view of the mechanism for opening the cloth shearing elements for the passage of the seam, the cloth rest being shown in non-active or open position in relation to the shear blades.

Fig. 3 is an enlarged detail showing in right side elevation the detector or feeler mechanism, which energizes the means for opening and restoring the shearing elements for the passage of the seams.

Fig. 4 is a plan view of the feeler mechanism shown in Fig. 3 in association with the mechanism for opening the shearing elements, which is energized through the medium of the feeler mechanism.

Fig. 5 is a perspective view in detail showing a part of the feeler mechanism that is intended to prevent the opening of the shearing elements by a slab, knot or other isolated bunch on the face of the cloth.

Fig. 6 is an enlarged detail showing the constantly rotated sprocket and associated gearing by which, through the agency of the seam detector, the opening of the shearing elements is effected.

Fig. 7 is a front elevation of the seam-controlled opening mechanism shown in Fig. 6.

Fig. 8 is a side elevation of the adjustable timer control mechanism through the action of which the closing elements is effected in any desired predetermined time after they have been opened.

Fig. 9 is a front elevation of the timer mechanism shown in Fig. 8.

Fig. 10 is a side elevation corresponding to the view shown in Fig. 3 but illustrating a modified form of selective feeler mechanism where all the

feeler fingers are mounted in the same plane transversely of the travel of the cloth.

Fig. 11 is a plan view of the modification shown in Fig. 10.

5 Fig. 12 illustrates another modified form of selective feeler.

Fig. 13 shows a perspective view of the modified form shown in Fig. 12.

In the practice of the invention according to 10 the form illustrated in the drawings, the mechanism may be applied to any well known type of shearing machine. In this case we have shown it applied to a multiple blade shearing machine provided with shearing elements arranged to crop 15 or shear opposite faces of the cloth. In the type of machine illustrated, suitably mounted in the forward portion above the main frame A of the machine are two revolvers or rotary fly blades 1 carried by their respective shafts 1^a and associated 20 in each case with the usual relatively fixed ledger blade 1^b. Above each pair of blades are pivotally mounted on shafts 3^a inverted cloth rests 3, in this case of the gap or trough type, over which the cloth is stretched when passing 25 by the shearing line formed between itself and each pair of blades 1 and 1^b. The cloth rests are fulcrumed on transverse shafts 3^a which are oscillated by rocker arms 3^b, 3^c, which are interconnected with each other by means of a connecting link 5 which is made extensible by means 30 of a turn buckle 5^a.

The rearmost shearing couple in this machine comprises the fly blade 2 and its relatively fixed associated ledger blade 2^b located above the cloth 35 supporting rest 4 fulcrumed on rock shaft 4^a, which is provided with a rocker arm 4^c that is interconnected with the rocker arm 3^c by means of a similar connecting link 5 provided with an 40 adjusting turn buckle 5^a in accordance with well known practice.

Fast on the rock shaft 4^a is an actuating spider 45 comprising arms 4^b, 4^d and 4^e. Pivotally attached to the arm 4^d is a link 7^a, which is connected with an adjusting anchoring screw 7^b by means of a retractile spring 7 which normally 50 acts to restore and maintain the interconnected cloth rests in their closed or operative relationship to each associated pair of shear blades.

Pivoted on a fixed portion of the frame is a 55 cloth rest supporting latch 6, which retains the cloth rest members positively against displacement from operative position.

The cloth rests, by means of their intermediate 60 link connections, are simultaneously actuated toward or from the shearing line to open a space between the shearing elements sufficient to allow 55 the seamed ends of the cloth to pass by without being cut by the shear blades.

The opening of the shearing elements, in this 65 case accomplished by the movement of the cloth rests away from the shear blades, is accomplished by means of the link bar 8, which is connected with the arm 9 on a rock shaft 9^b extending transversely at the forward part of the machine. A 70 retractile spring 9^c tends to move the bar 8 forwardly. Adjustably clamped on the bar 8 by means of the clamping bolt 8^b is a latch-actuating member 8^a, which moving rearwardly with the rearwardly moving link bar 8 acts first to release 75 the latch 6 to allow the cloth rests to move away from the shear blades to open position. The rear end of the link bar 8 is provided with an elongated slot through which passes a connecting bolt or stud 8^c carried by the arm 4^b, which is secured 80 to the rock shaft 4^a of the rear cloth rest. This

stud 8^c is located so as to be a short distance from the front end of the slot in link 8 when the cloth rests are in normal operative position so as to permit the latch-actuating boss or member 8^a to open the latch before the forward wall of the slot begins to thrust against the stud 8^c and swing the rock shaft in a counterclockwise direction to open the rests. When the rests are swung to open position, as indicated in Fig. 2, by this rear movement of the link 8, a hardened plate 4^x 10 on the tip end of the arm 4^b is caught behind a similar plate 51 carried on the angle or bell crank lever 50, 50^a mounted on the pivot 50^b, this dog or bell crank arm being normally forced to its limit of movement in a clockwise direction 15 by a spring. Therefore, when the link bar 8 moves to this rearward limit of movement under actuating means, presently to be described, the arm 4^b fastened to the rock shaft 4 is retained in that position, while the slot in the link bar allows 20 the spring 9^c to return the bar 8 to its forward position without releasing the cloth rest from open position. This release is accomplished by timing mechanism whose construction and operation will later be explained. 25

The mechanism, particularly concerned in the automatic control to let the seam pass the shear blades, comprises generally speaking a group of parts at the forward end of the machine designated as I, which comprise essentially the feeler mechanism; a second group of parts designated as II in the drawings, which forms the cloth rest opening mechanism; and a third group of parts designated as III at the rear of the machine constituting the timing mechanism for determining 30 the time of return of the cloth rest to normal position. As is well known in the art, the opening of the shearing elements may be effected either by movement of the cloth rests away from the shear blades, or by the movement of the 35 shear blades away from the cloth rests. For purpose of illustration we have in this case shown the cloth rests as the moving elements under the control of the automatic opening mechanism, which separates them from the shear blades, but 40 it will be obvious that similar mechanism might be used to actuate the pivotal frames which carry each pair of shear blades. 45

The mechanism for opening the shearing elements, in this case the cloth rest elements, includes a link 10 which at its lower end is pivotally connected with a rotatable arm 14 loosely supported on a shaft 11 to which shaft is secured a continuously rotating sprocket wheel 13 driven by a sprocket chain 13^a from a power or counter 55 shaft B mounted in the rear portion of the frame A. The rocker arm 14, loose on the shaft 11, is actuated only when it is interconnected with the shaft 11 through the agency of the seam-controlled mechanism or group I. The connection 60 between this rocker arm 14 and the continuously rotating shaft 11 is best shown in Fig. 1, Fig. 6 and Fig. 7. Mounted in a laterally extending boss of the sprocket wheel 13 is a rotatable spindle 12^a carrying at its near end a pinion 15 and 65 at its farther end a pinion 12. Loose on the shaft 11 on the same side of the sprocket as pinion 15 is an intermeshing pinion 15^a, which is compounded or fastened to the hub of the rocker arm 14, so that pinion 15^a and rocker arm 70 14 constitute a single unit. Loose on the farther end of the continuously driven shaft 11 is a gear or pinion 18, with which is compounded or fastened integrally a ratchet wheel 17^a adapted to be engaged by a ratchet pawl 17, which is fast 75

on the spindle 19^a that is normally rotated in a clockwise direction by a tensioning spring 19^b but is held against the pull of the spring 19^b by a projecting finger or arm 19^c which is normally engaged by a seam-controlled member presently to be described.

When the pawl 17 is held out of engagement with the ratchet wheel 17^a, the shaft 12^a, to whose opposite ends are secured the pinions 15 and 12, revolves with the sprocket member 13 in a counterclockwise direction, the two planetary pinions 15 and 12 simply rolling around their corresponding pinions 15^a and 18. Inasmuch as the then stationary pinion 15 and pinion 15^a have an equal number of teeth, say 15 teeth, and inasmuch as pinion 12 has only 12 teeth intermeshing with the larger pinion 18, having let us say 18 teeth, it is obvious that while this planetary movement of the spindle 12^a takes place the pinion 18 will be rotated more slowly than the sprocket and in reverse direction.

When, however, the ratchet pawl 17 is thrown into interlocking engagement with its ratchet wheel 17^a that is secured to the toothed pinion 18, then this compound element or ratchet-pinion is held against rotation and the planetary movement of the small pinion 12 rolling around the stationary pinion 18 will actually impart to pinion 15^a a somewhat more rapid rotation than the rotation of the driving sprocket and in a direction opposite to the direction of rotation of the driving sprocket, so that the rocker arm 14 fast to said pinion 15^a will revolve in a clockwise direction acting through link 16 to rock the shaft 9^b in a clockwise direction, thereby forcing the link 8 rearwardly releasing the latch 6 and pushing the arm 4^b until its hook plate 4^x engages the rear shoulder of the plate 51 on the dog 50. The shearing elements are now opened and after the pawl 17 is released from its ratchet 17^a the link arm 8 will be retracted forwardly to its normal position by the spring 9^c.

It will therefore be seen that the power driven mechanism for opening or separating the shearing elements is energized for action by means of the pawl 17, which is normally kept out of its active or operative position by a stop finger 19^c on the shaft 19^a which stop finger is engaged and held out of action, as best shown in Fig. 3, by a downwardly extending arm 38^b which is secured to the overhead rock shaft 38 and which carries at its lower end an antifriction roller or bowl 36^c. As the rock shaft or spindle 19^a is normally pulled in a clockwise direction by the retractile spring 19^b (Fig. 1) it is evident that movement of the roller 36^c in a clockwise direction out of the path of the tip of the stop finger 19^c will allow the pawl 17 to instantly engage the ratchet 17^a through which the opening of the shear mechanism is effected, as above described.

One of the outstanding difficulties experienced with automatic seam-controlled shears is due to the fact that in previous automatic seam-controlled shear separating mechanism, such mechanism once started in action necessarily continues through a definite cycle, such as effected by the rotation of a controlling cam, at the end of which cycle the shearing elements are re-established in closed relation either by return of the cloth rest, or by the shear blade head, and no provision is made to prevent the re-establishment of the closed relation in case a knot, bunch or other excrescence on the cloth actuates the feeler mechanism to energize the shear opening mechanism. Now, it is a common occurrence

to find, here and there, scattered at random through the face of the cloth, bunches or excrescences which will act, through the feeler mechanism, to energize the shear controlling mechanism. If such shear opening mechanism is energized by such a bunch near enough to a seam in the cloth that follows it, the seam will pass by the feeler without any other result than to move the feeler, since the shear opening mechanism is already in operation to perform its uninterrupted cycle unaffected by the movement of the feeler at that stage. Consequently, for this reason it very frequently happens that the blade-raising or rest-moving mechanism allows the shearing elements to close to normal shearing position after the seam has passed the feeler and is approaching the shearing line. The result is that the cloth is likely to be badly cut at the seam and often times the shearing blades will be broken when encountering this extra thickness produced by the seam. On the other hand, individual knots or slubs on the face of the cloth can readily pass between the shearing elements when in operative position without damage to the cloth. Indeed, these excrescences on the cloth are usually cropped off by the shearing elements in such case, which is of obvious advantage in the cloth finishing operation.

To eliminate injury to the cloth or damage to the shear blades by such occurrences as above described, we have provided a construction and arrangement of feeler mechanism for controlling the opening of the shearing elements comprising substantially a plurality of feeler fingers that are laterally offset in spaced relation transversely to the travelling cloth and so combined, or associated, that unless all of the feeler fingers are actuated at practically the same time the feeler mechanism will remain inactive so far as the energizing of the shear opening mechanism is concerned. Obviously any number of narrow fingers may be arranged at intervals across the width of the travelling cloth, but in the present mechanism illustrated in the drawings the principle is properly illustrated by the use of three mutually related feeler fingers, whose arrangement and operation will now be described.

On the front of the machine frame A are provided two side brackets or frames 20, which form the support for round crossbars or girts 21, 22 and 23, which serve as supports for the feeler mechanism. On girt 22 is secured an upwardly projecting arm or bracket 22^b carrying a cloth-engaging idler roll 22^c capable of very free rotation. On opposite sides and some distance away from this fixed bracket 22^b, there is secured to the girt 22 a pair of brackets 24 having a rearwardly and downwardly extending arm 24^a and a downwardly and forwardly extending arm 24^b carrying a freely rotatable cloth-engaging roller 24^c.

The rearwardly and downwardly extending arms 24^a of these two brackets carry a slowly rotating spindle or shaft 25, which is rotated in a counterclockwise direction by means of a belt and pulley connection between a small pulley 11^a on the end of the sprocket driven spindle 11 and a larger pulley 25^a secured on the near end of the shaft 25, as shown in the plan view, Fig. 4. Fast on this spindle 25 is a ratchet 26 and adjacent to the ratchet, and loosely pivoted on the ratchet spindle 25, is a hub member having a forwardly projecting arm 27 and a rearwardly and upwardly projecting arm 28. Adjustably se-

cured to the short arm 27 by means of screw and slot connection is a forwardly projecting narrow blade of sheet metal forming, in this case, a preliminary feeler finger which normally overbalances the rearward arm 28, either by gravity or by light spring tension not shown, so that the forward tip of the feeler finger 27^a rests lightly upon the fixed crossbar 23, in front of which the cloth x passes upward by the tip of the feeler finger 27^a.

As best shown in Fig. 5, the arm 28 carries at its outer or rear end an antifriction roller or bowl and near its inner end carries a pawl 29 adapted to drop into and engage the teeth of the ratchet 26. When a seam or other thickness, such as a knot or slab engages the tip of either of the preliminary fingers 27^a, because this mechanism is duplicated on both sides of the bracket 22^b, the angle arm construction embracing arms 27 and 28 is rocked in a clockwise direction about the shaft or spindle 25 that is slowly rotating in a counterclockwise direction. This clockwise rocking of the arm 28 moves its bowl clear of a finger 39 that is mounted on the rock shaft or spindle 38, thus allowing the rock spindle 38 to rock in a clockwise direction.

As best understood from Fig. 3 and Fig. 4, intermediate of the two brackets 24 on the girt 22 is secured a third bracket fast on the girt 22 having a rearwardly extending arm 22^a and an upwardly extending arm 22^b carrying a freely rotatable bowl 22^c likewise engaging the rear face of the cloth some distance above or beyond the bowl 24^c. In this rearwardly extending arm 22^a is mounted a horizontal rock spindle 38, whose near end is supported by another bracket 22^d secured to the girt 22. Intermediate of the vertical planes of the two feeler fingers 24^b is a similar finger 36 secured to the rock spindle 38 and projecting forward to engage the rear face of the cloth. This upper feeler finger 36 is adjustably fastened to an arm 36^a fast on the rock spindle 38 by a screw and slot connection to permit the proper adjustment of its tip to the line of travel of the cloth x . The feeler finger 36 is lightly pressed by a spring plunger 35 carried by the arm 22^a against an adjustable stop screw 34. The arm 36^a has a downwardly extending arm 36^b carrying at its lower end the bowl 36^c, which, so long as it engages the finger 19^c on the rock shaft 19^a, prevents the movement of the pawl 17 into engagement with the ratchet 17^a, whose arrest by the pawl, as previously explained, energizes or sets in action the rest operating arm 14 to open the cloth rest for the passage of the seam.

Let us suppose that a relatively narrow slab or bunch on the cloth is approaching from below the bar 23, which acts as a stop for the feeler fingers 27^a, and that such slab or knot is in line with one of these feeler fingers. It will therefore act to swing feeler finger 27^a in a clockwise direction, thus moving arm 28 and bowl 28^a out of stop engagement with an arm 39 attached to the rock shaft 38, leaving the rock shaft free to rock in a clockwise direction. Such rocking action of the rock spindle 38 will be effected only when the upper feeler finger 36 is engaged by a projection or excrescence, but if the relatively narrow slab or knot is in longitudinal alignment with one of the fingers 27^a it will be offset in relation to the vertical plane of the finger 36. Consequently it will not cause the feeler mechanism to function because, unless the finger 36 is swung upward and the rock shaft 38 rocked, the bowl 36^c on arm 36^b will not be cleared from the detent

finger 19^c of the rock shaft 19^a which engages the pawl 17 with the ratchet. Furthermore, should a slab in alignment with the finger 36 pass by both of the preliminary feeler fingers 27^a and engage the tip of the finger 36, the rearwardly projecting arms 39 engaging, respectively, the bowls 28^a on the transversely spaced rock arms 28 would normally prevent the rocking of the rock spindle 38 and therefore the stop finger 19^c would not be cleared to allow the pawl 17 to act.

Obviously, therefore, a seam extending across the entire width of the cloth must actuate or tilt all the feeler fingers so that the bowls 28^a are moved clear of the stop arms 39 and the master feeler finger 36 will be swung upward to rock the spindle 38 and release the bowl 36^c from stop engagement with the finger 19^c on the rock shaft 19^a.

There are, however, several refinements of this feeler mechanism, the details of which we will now explain. In sewing together numerous pieces of cloth end to end it frequently happens that some of the pieces to be cropped or finished are much thicker than are other pieces and an arrangement or adjustment of feeler fingers, that would be appropriate for close contact with the thin pieces of the cloth without being actuated, might easily be actuated by a thick piece of cloth at points where there was no seam. It will be understood that it is customary and desirable to place opposite the tip of the feeler finger an opposing member or cloth guide to prevent the cloth from swinging out away from the feeler finger and thus allow seams to pass by without actuating the feeler finger. In our present invention, we have provided adjacent to the location of the feeler fingers opposed guide members which serve to guide the cloth properly by the tip of the feeler fingers so as to insure working engagement of the passing seam with the feeler fingers, while at the same time providing compensation for different thicknesses of cloth to avoid the undesired actuation of the feeler fingers by the passage of a relatively thick piece of cloth, as above explained.

Since in the present form of our invention illustrated in the drawings we have provided lower and upper ranks of feeler fingers for the purpose above described, we use two of these compensating cloth guiding elements one above the other which we will now describe.

Suspended from, and secured to the upper forward cross girt 21 is a fixed bracket 21^a which serves as a support for a swingable arm 30 mounted on a pivotal center 30^a and normally pressed in a counterclockwise direction by a light spring pressed plunger 30^b against an adjustable stop screw 30^c carried by the fixed member 21^a. Some distance below the pivotal center 30^a a freely rotatable cloth contacting or guiding bowl 32 is mounted in direct opposition to the bowl 22^c mounted on the fixed arm 22^b. Below the center of the bowl 32 the swinging arm 30 has its rear face planed smooth to lie substantially parallel with the plane of the upward travelling cloth. The stop screw 30^c permits an adjustment that prevents the spring plunger 30^b from squeezing the interposed cloth tightly against the bowl 22^c that supports the back face of the cloth.

Other depending brackets 21^b on either side of the plane of the brackets 21^a, also secured to the girt 21, serve as a support for similar pivotal arms 31 carrying below their pivotal axes 31^a each a bowl 32^a directly opposed to the bowls 24^c, which latter bowls form non-yielding, easily rotated sup-

ports for the back face of the cloth. These lower swinging arms 31 are also urged by spring plungers 31^b toward the bowls 24^c, but such rearward movement is limited by the adjustable stop screws 31^c.

The small girt 23, which forms a stop for the feeler fingers 27^a, also acts as a guide for the cloth approaching the feeler member. It will therefore be seen that the front face of the cloth is lightly pressed toward the rear non-yielding bowls 22^c and 24^c and that the short stretches of cloth approaching the respective bowls are guided by the flat rear faces of the lower ends of each of these swinging arms. Suppose now a thin piece of cloth is passing through the feeler mechanism followed by a thicker piece. This thin piece will pass between each pair of opposed bowls being kept lightly pressed against the two non-yielding bowls 22^c and 24^c by the compensating members 30 pressing against the front face of the cloth. When the sewing or seam uniting a thin piece with a relatively thick piece passes the lower feeler fingers 27^a, it will actuate that finger and the master finger above it and the following thick stretch of cloth will act to move the bowls 32^a and also the bowl 32 and their corresponding supporting arms slightly outward to compensate for this extra thickness but still maintaining the cloth in a proper plane of travel for the next seam to engage and actuate the feeler fingers when it passes through. It will therefore be seen that we have provided cloth guiding means that maintains the cloth in a proper plane of travel to permit the seams to engage the feeler fingers, while at the same time yielding to compensate for extra thicknesses of cloth without causing such extra thickness of itself to actuate the feeler mechanism and so thin pieces of cloth are maintained in the appropriate plane to insure their seams engaging and actuating the respective feeler fingers.

Now it may sometimes happen that a seam, wrinkle or the like may produce sufficient thickness to wedge the cloth against a feeler finger or fingers in such a way as to cause a jam, which the limited movement of the compensating members may not suffice to relieve, while at the same time the master finger 36 is held by its rearwardly extending arm 39 from yielding to permit the extra thickness or fold to pass by. This will be of rare occurrence but provision is made for dealing with such conditions by making a yielding joint or connection between the stop arm 39 carried by the rock shaft 38 and the forwardly projecting feeler finger 36 secured to said rock shaft.

It will of course be understood, as shown in Fig. 4 of the drawings, that the stop arms 39 are vertically aligned with the arms 28 of the preliminary feeler mechanism, while the feeler finger 36 is transversely offset in relation to the feeler fingers 27^a and the stop arms 39. Accordingly there is secured to the rock shaft 38 adjacent to each stop arm 39 a short arm 37, that is pinned or keyed to the rock spindle 38, while the hub 39^a, which carries the stop arm 39, is loose on the shaft 38, as shown in Fig. 5. To preserve normal operative relationship between the feeler finger 36, which is fast on the spindle 38, and the loosely mounted arm 39 carried by said spindle, there is provided a retractile spring 37^b attached to the arm 37 and to an underneath projection from the arm 39, which serves to draw and hold the arm 39 against an adjustable stop screw 37^a carried by the arm 37. This arrangement permits the adjustment of the arm 39 to a proper angle 75 in relation to the feeler finger 36, while at the

same time providing a yieldable joint that presents sufficient resistance to the flexing of the joint when an ordinary slab or knot passes by the tip of the feeler finger 36, while at the same time acting to relieve a jam caused by an unusually thick wedging of the cloth that the yielding movement of the compensating member 30 is unable to relieve.

Of course, it is barely possible that there may be knots or slabs occurring at sufficiently close 10 intervals across the cloth to actuate all the feeler fingers simultaneously and thus opening the shearing elements. Such an occurrence, however, is extremely unlikely, particularly if the number of feeler fingers spaced transversely of 15 the cloth be increased but even should such an unusual condition occur, no harm would result because it would merely actuate the feeler mechanism to temporarily open the shearing elements to let such slabs pass through. Because of the 20 yielding properties of the compensating cloth guides, the small slabs and knots would not cause the actuation of the feeler fingers, but if any are large enough to actuate the feeler fingers they must be so disposed over the face of the cloth 25 to engage all the feeler fingers practically at the same time.

In order to prevent too rapid return of the feeler fingers 27^a and to give sufficient time for the seam to actuate master finger 36 before arm 28 30 has returned to stop position, a pawl 29 on arm 28 rides over the slowly rotating ratchet 26 when the arm 28 is swung in a clockwise direction to free the arm 39 by the return movement of the arm 28 and its attached feeler finger 27^a is rendered very slow through the engagement of the pawl 29 with the slow moving ratchet. Only a very brief interval elapses before the cloth passes from the preliminary feeler finger to the master finger anyway, but this ratchet and pawl arrangement positively insures retention of the arm 28 35 out of stop engagement with arm 39 until the seam has passed beyond the master feeler 36.

Not only is it necessary to return the shearing elements to closed relation to perform their function of cropping the face or faces of the cloth, but it is highly desirable that the closing of the shearing elements should occur as soon as practicable after the seam has passed the shearing line or, where there are several pairs of shearing 50 elements, the shearing line of the last pair of such elements. It is the object and function of the mechanism constituting group III of the control mechanism to effect the closing of the shearing elements within a predetermined but 55 variable time, so that the shearing or cropping operation may be promptly resumed after the passage of the seam.

As above explained the dog 50, 50^a operates as a latch or detent to hold the arm 4^b in its retracted position to retain the cloth rests in open position. The release of this latch or detent will permit the cloth rest to move to closed position under the operation of the actuating spring 7 or any other actuating means that may be employed for that purpose.

At the rear of the machine is a transverse constantly rotating shaft C driven by sprocket chain C' from the driving shaft B and on this shaft C is a cloth feeding or traction roll, which revolves in a counterclockwise direction as viewed in Fig. 1. The cloth passing around a considerable portion of the periphery of this drum C² is drawn through the machine back of the rear shearing line. On the end of this shaft is a spiral 70 75

or skew gear 60 which intermeshes with a similar gear 61 on a worm shaft 62 at right angles to the axis of the shaft C. The worm on this shaft engages a worm gear 63 to which is imparted a 5 very slow rotation as compared with the speed of rotation of the drum C². Securely fastened to the worm gear shaft 64 is a ratchet 65 and adjacent to said ratchet the shaft 64 carries a loose disc 66 on which are pivotally mounted, at centers equi-distant from the axis of the shaft, a series of ratchet pawls 67. These ratchet pawls have their points yieldingly held in contact with the ratchet 65 by means of contractile springs 68 connecting pairs of adjacent pawls, as illustrated 10 in Fig. 8 and Fig. 9. This loosely mounted pawl disc 66 is normally pulled in a counterclockwise direction by means of a contractile spring 68^a.

Compounded with, or integral with, the pawl disc 66 is a member in the form of a bell crank 20 lever comprising the arms 55, 56. The right hand arm 55 is provided with a pin 55^a passing through a slot in the rear end of a link 57, whose forward end is pivotally attached to the rest-actuating link 8 so that, when the link 8 is forced rearwardly by the arm 14 to release the rest supporting latch 6 and drop the cloth rest 4 away from the shear blades to open position, the bell crank arm is pushed rearwardly in a clockwise direction.

30 Now the left hand arm 56 of this bell crank lever has a swivel connection with a sleeve 54 through which passes a sliding link 53 having adjustable stop nuts 52 on its forward end. The rear end of this link 53 is pivotally connected 35 with the outer end of latch arm 50^a. A helical compression spring 58 surrounds the link 53 and is interposed between the sliding swivel sleeve 54 carried by arm 56 and a stop on the pivoted or rear end of the link 53.

40 The clockwise movement of the arm 56 causes the swivelled sleeve 54 to slide along the link rod 53 to compress the spring against its rearward stop on the link 53, as shown in Fig. 2, so that the latch 50, 51 is held in firm latching engagement with the tip of the cloth rest arm 4^d. This clockwise movement of the bell crank arm 55, 56 which compresses the spring 58 is caused by the rearward push of the link 57 and reaches substantially the same backward point on successive operations. As soon as the link 8 and the connected link 57 are free to return to normal or forward position by means of the spring 9^c, the bell crank arm 55, 56 integral with the pawl carrying disc 66 will tend to return to initial or forward position, but on such return movement the member 55, 56 is retarded by means of the ratchet and pawl engagement with the slowly rotating ratchet shaft 64 so that the return movement is normally slower than would be the return movement of the 60 links 8, 57, which are permitted to return to forward position in advance of the bell crank arm 55 by reason of the lost motion or pin and slot connection 55^a.

65 Now the return or forward movement of the arm 55 is utilized to unlatch the dog 50 from the downward arm 4^b projecting from the cloth rest rock shaft 4^a, but this unlatching movement will not begin until the sleeve 54 abuts against the adjustable stop nut. Consequently, the time 70 of this return movement, which is under the control of the slow moving ratchet and pawl connection, is determined by the arc of movement of the arms 55, 56 which may be varied by adjustment of the stop nut or thrust nut on the link 53. 75 There is provided then a simple adjustment by

which the duration of the open period of the shearing elements is controlled because just as soon as the latch 50 is disengaged from the arm 4^b the shear closing mechanism is free to act. It is a simple matter for the shear operator, when running through a strip of cloth, to adjust this timing mechanism so that the shear elements will close promptly after the seam has passed through the last pair of shearing elements. Since the forward or return movement of the pawl arm 55 is free to start as soon as the link 57 and the link 8 start to move forward from their rearmost or rest opening position, and since that return movement is controlled by a constantly rotating ratchet, the duration of the retention of the cloth 15 rests in open position can be very accurately controlled, since the closing mechanism starts with the completion of the opening movement. To avoid objectionable lost motion or back lash in this ratchet action, we prefer to use a plurality 20 of pawls and to locate the tips or points of these pawls 67 so that the different pawls will stand in different relation to the rear abutment face of each tooth of the ratchet, which lies in front of it. Suppose for example that each ratchet tooth 25 measures one-eighth of an inch in a circumferential direction. Then, by circumferentially offsetting the pawls they may be positioned so that when any individual pawl has its point firmly thrusting against the rear abutment of the tooth 30 ahead of it the other pawls will be separated by equal increments of spacing so as to subdivide the circumferential length of the teeth into six parts, where six pawls are used, which would result in there being only a very slight, if any, 35 lost motion between the tooth that in any given operation actually engages its corresponding ratchet tooth. Furthermore, the use of this offset spacing of the pawls, so that only one individual pawl is actually working on each return 40 movement of the cloth rests, serves to distribute the wear among the different pawls instead of concentrating it on a single pawl.

This control or checking of the return movement prevents the delivery of a strong blow or 45 shock upon the rest-retaining latch mechanism and a somewhat similar checking or restraining action may be employed to prevent shock when the cloth rests themselves are returned to closed position, for it will be understood that the action 50 of the cloth rest returning spring 7 would naturally operate as soon as the cloth rest shifting arm 4^d is released from the latch 50. Such return would tend to be very rapid until the cloth rest reached its limit of closing movement.

55 Referring now to the mechanism constituting group II, it will be seen that the arm 14, operatively connected with the rest opening link 8, is provided at its short end with a cam surface 14^a dimensioned to engage and move forwardly the 60 pawl 14 on the free end of the arm 19 attached to the spindle 19^a, so that by the time the arm 14 has travelled to its final rest-opening position, as illustrated in Fig. 2, the arm 19 has rocked the spindle 19^a in a counterclockwise direction 65 sufficiently to disengage the pawl 17 from the ratchet 17^a. When the pawl 17 is thus disengaged, the return movement of the arm 14 is permitted under the pull exerted by the return spring 9^c until such time as the rear end of 70 the slot in the link 8 engages the pin 8^c carried by the arm 4^b of the cloth rest spider. So long as the arm 4^b is held in retracted position by the latch 50, the complete return movement of the link 8, the arm 9 and the arm 14 is prevented, 75

but on the release of the latch 50 the remainder of the return movement of parts 14, 9 and 8 is permitted.

We have provided checking means in group II 5 for preventing shock as to both parts of this return movement of the cloth rests. Referring particularly to Fig. 6 and Fig. 7, it will be seen that between the sprocket member 13 and the pinion 18 there is mounted on the hub of the 10 pinion 18 a member 16, which has a frictional engagement with the annular bearing face of the hub which supports it, but which can be moved thereon independently of the pinion 18. Mounted on a pin 13^b that projects laterally from 15 the sprocket member is a pawl 18^a, which is normally drawn into contact with the teeth of the pinion 18 by means of a contractile spring 18^b attached thereto and attached also to a pin 13^c likewise projecting from that face of the sprocket 20 wheel. The pointer tooth of this pawl, as indicated in Fig. 6, is formed to allow rotation of the pinion 18 in a clockwise direction but to hold it against rotation in a counterclockwise direction just as does pawl 17, engaging the ratchet 25 17^a, but it differs from pawl 17 in that pawl 18^a is carried by the constantly revolving sprocket wheel instead of being carried on a non-revolving rock shaft, as is the pawl 17. The arm 16, whose hub frictionally surrounds the hub of the pinion 30 18, as above described, has its outer end notched to form spaced teeth 16^a, 16^b straddling the arbor 13^b that carries the pawl 18^a, so that these teeth permit a certain relative oscillation or lost motion of the arm 16 until one or the other of 35 the teeth 16^a, 16^b engage against the pin or arbor 13^b.

Now, as previously explained, the arrest of the unit 17^a, 18 against rotation will result in a clockwise revolution of pinion 15^a, which is united 40 with arm 14 to produce rotation of said arm 14 in a clockwise direction to open the shearing elements, but if arm 14 is energized by the cloth rest return mechanism to rotate in a counterclockwise direction similar to that of the sprocket 45 et 13, then the pinion 18, no longer being restrained by the pawl 17, is free to rotate in the same direction as the sprocket wheel 13 but at a much more rapid speed if the cloth rest return means are exerting considerable force to 50 rotate the arm 14 in a counterclockwise direction. Therefore, if the pawl or latch 18^a, which is carried by, and travels with, the sprocket element 13, is engaged with the pinion 18, the latter cannot revolve under the urge of the arm 14 and 55 the interconnecting pinions any faster than does the sprocket element which carries the pawl, so that the sprocket and pawl connection acts as a check to retard the return movement of the link 8 and of the cloth rests to final closed position. The member 16 is employed for the purpose of disengaging the dog or pawl 18^a from the pinion 18 and is provided with a laterally projecting pin 16^c for engaging the inner face of the pawl to throw it outward when the arm 14 has completed its return movement to normal 60 position, at which time the arm 14 ceases to accelerate rotation of the pinion 18 in the same direction as the rotation of the sprocket. At this position of the mechanism, the arm 14 acts as a stop or arrester for the pinion 15^a, thus producing a slow counterclockwise direction movement of the pinion 18. In this counterclockwise rotation of the pinion 18, the release member 16, which is frictionally engaged therewith, tends to 65 participate in this movement until the tooth 16^a

thereof is stopped by engagement with the pin 13^b, but the pin 16^c partaking of this clockwise rotation of the member 16 with the pinion 18 engages the inner face of the dog or pawl 18^a and holds it in outward or inactive position but, 5 as the member 16 is only frictionally engaged with the pinion 18, the engagement of its pin on the front face of the disengaged pawl 18^a will cause it to rotate with the sprocket in such release relationship to the pawl 18^a. It will remain in such relationship until the return movement of the arm 14 again tends to cause the pinion 18 to overrun in the same direction of rotation the sprocket 13, thus permitting another engagement of the pawl with the ratchet to 10 function as above described.

It will of course be understood that the action of the pawl 18 and of its control member 16 is not vital to the operation of the mechanism as an entirety, its real purpose being to prevent 20 sudden shock or jar which would result from the quick unrestrained return of the cloth rest actuating means, and using 16 to hold out pawl to prevent its wear.

While in Fig. 1, Fig. 2 and Fig. 3 we have shown 25 the feeler fingers arranged in different planes to form the selective feeler mechanism, yet we desire it to be understood that this tandem arrangement with preliminary feelers, arranged in advance of the master feeler, is not the only form of embodying this principle of selective feeler mechanism and therefore we have shown in Figs. 10 to 13, inclusive, two modified constructions and arrangement of feelers for accomplishing this same 30 result of selective action which permits isolated 35 knots or bunches to pass by without causing separation of the shearing elements, while insuring action by the feeler mechanism to open the shearing elements through contact with the transverse seam. 40

In the forms shown in Figs. 10 and 11 we have simply omitted the preliminary set of feeler fingers and provided in transverse axial alignment plural feeler fingers arranged at spaced intervals in a coaxial series transversely of the cloth, each 45 unit being independently movable from the other feeler unit or units so as to permit any individual feeler unit to be moved by knots or bunches engaging it without energizing the shearing opening mechanism, unless all the feeler units are simultaneously actuated which, as before explained, could occur only in the remote contingency that all the feeler units should be simultaneously actuated by knots or bunches in line with each of the 50 entire series of feelers. 55

In this modified form shown in Figs. 10 and 11 we employ the cloth engaging guide roller 22^c mounted on an arm 22^b carried by the girt 22 and we also provide rearwardly extending arms 22^a secured to said girt in position to support a rock shaft 36^d which, as shown in Fig. 11, is subdivided into aligned sections. These rock shafts each carry a pair of feeler fingers 36 well spaced apart, whose forward or outer ends are positioned to graze the rear face of the cloth x. Should a knot or bunch of limited width engage either individual feeler finger of each feeler finger unit, the rock spindle 36^d would be tilted to throw the 60 downwardly projecting arm 36^b forward out of engagement with the stop finger 19^c secured on the rock spindle 19^a which carries the energizing pawl 17. One or more similar units of these feeler fingers are similarly mounted, so that the action 65 of any feeler unit in the series in freeing its sub- 70 75

tending stop finger 19^c would not result in allowing the spindle 19^a to rock to pawl-engaging position, because the companion feeler finger unit would not be actuated to release its subtending arm 19^c but would hold the rock shaft 19^a against pawl actuating movement.

It will of course be understood that the yielding arm 30, carrying cloth engaging roller 32 toward fixed roller 22^c on the arm 22^b, acts precisely as previously described in reference to the preferred form. Such arms act through the swingable roller 32 to adjust themselves according to the thickness of the piece of cloth passing through, while retaining either thick or thin pieces of cloth, as the case may be, in close proximity to the adjacent feeler finger 36 to insure engagement of the feeler by aligned bunches on the cloth.

Fig. 12 shows a plan view of this cloth guiding means with a modified form of feeler finger. In this case, the feeler finger comprises a rear portion 72 provided with an upstanding lug 73 and having a forward extension 74 provided with a forwardly projecting pin 75. On this pin is mounted a light sheet metal fork 76 notched to form spaced fingers 76^a and mounted on a rock shaft 36^d to which it is secured, so that the raising of the feeler finger rocks the shaft and frees the stop finger 19^c from the restraint of the downwardly depending arm 36^b, as previously explained. A narrow knot or bunch approaching this form of feeler finger might either pass between the two projections 76^a of the fork or it might engage either one of them. In the former instance, the feeler finger would not be actuated at all. In the second case, the fork would be rocked on the axis 75 to yield and allow the narrow bunch to pass by without raising the finger. The fork is normally kept in horizontal position by means of a spring 77 connecting its off-center portion with the lug 73, so that the fork thereof, permitted to rock axially when engaged on either prong, is restored to horizontal position as soon as the knot has passed.

It will therefore be seen that in all forms of the feeler mechanism the action is a selective one in that it allows knots or narrow protuberances engaging the feeler to pass by without completing actuation of the shear opening mechanism, while at the same time the feeler mechanism is completely responsive to a seam that extends across the width of the cloth. This principle of selective feeler is believed to be entirely new in the art and is of great importance in preventing the opening of the shearing elements when they ought not to be opened. On the other hand, although the feeler mechanism is selective in its operation, yet when a seam does engage it the action of the feeler mechanism in opening the shearing elements is so rapid that the cloth may be safely run through the machine at high speed.

Moreover, since the closing of the shearing elements, after the seam has passed the last shearing line, can be so accurately gauged as to effect shearing throughout the length of each piece of cloth, except a very narrow area adjacent to the seam, the arrangement, therefore, permits very complete and effective shearing of the cloth while avoiding frequent unnecessary opening of the shearing elements which leaves the passing portions of the cloth unsheared, while at the same time eliminating the danger of cutting and damaging the cloth as well as the shear blades, which is present in automatic arrangements based upon the complete cycle operation, that is,

the complete revolution of an actuating cam or like member.

The rocker arm 14 is moved quickly to shear opening position and is released therefrom by the action of its own cam portion at that position to disengage the energizing pawl 17 so that the link connections, that open the shear, are restored to position ready for instant further service if need be. At the same time that the link connections open the cloth rests there is started in action the adjustable timer mechanism which controls the return of the cloth rests to operative or closed position. It is therefore possible to vary at will the intervals between the opening of the cloth rest and the closing thereof and at no time is the opening mechanism not subject to the control of the feeler mechanism. Furthermore, since any actuating movement of the shear-opening mechanism occurring at any stage of the open period of the shearing elements acts to restore to initial or starting position the member 56 of the timer that releases the latch for retaining the rest in open position, the normal duration of the open period may be repeatedly prolonged as often as the arm 14 of the operating mechanism is actuated through the medium of a seam or of an unusually large bunch or aggregation of bunches acting through a feeler mechanism. Obviously, therefore, the movement of the rest controlling mechanism may be interrupted at any time to prolong the open status of the shearing element instead of operating as heretofore only on a fixed predetermined cycle of movement that cannot be suspended or interrupted after once started. This feature of permitting interruptions of the action of the means for controlling the relation of the shearing elements is believed to be wholly novel in the art and is of very great practical importance in preventing injury to the cloth and damage to the shearing blades, such as occurs with prior devices when a seam passes the feeler mechanism shortly before the completion of the cycle of a seam-protecting mechanism that has already been started in operation by a lump or bunch on the cloth.

What we claim is:

1. In a cloth shearing machine embracing separable shearing elements the combination with a feeler device movable through contact with a cloth-seam approaching the shearing elements, of mechanism energized through the seam-induced movement of said feeler device to open the shearing elements for the passage of the seam between them, and means energized by a second actuation of the opening mechanism while the shearing elements remain open to prolong the duration of the open relationship between the shearing elements.

2. In a cloth finishing machine the combination with cloth-finishing means for operating upon the cloth, of seam-energized means for shifting the cloth finishing means to inoperative relationship, means for restoring the finishing means to operative relationship and adjustable timing means for prolonging the duration of such inoperative relationship by a second actuation of said shifting means in accordance with the adjustment of the timing means.

3. In a cloth shearing machine the combination with separable shearing elements, of seam-energized mechanism for momentarily opening the shearing elements for the passage of a seam, said opening mechanism being immediately returned to position for another operation after effecting the opening of the shearing elements,

means for restoring said shearing elements to operative relationship at a predetermined but variable period following the opening of the shearing elements, said restoring means embracing a timing control energized by the opening mechanism of the shearing elements.

4. In a cloth shearing machine the combination with separable shearing elements, seam-energized means for opening said elements for the passage between them of a cloth-seam, timing means restorable to its initial position at any time while the shearing means are open and thereby delay the return of said shearing elements to closed position after a predetermined but variable interval, and means for retarding the return of the shearing elements to closed position to prevent shock and jar.

5. In an automatic shearing machine embracing separable shearing elements, the combination with selective feeler mechanism rendered operative by a passing seam while remaining inoperative by the passing of relatively narrow bunches on the cloth, of mechanism for opening the shearing elements for the passage of the seam, said mechanism being energized through action of the selective feeler means and being immediately returnable to position for further operation after the opening of the shearing elements, means for retaining the shearing elements in open position, and a timer mechanism for releasing said retaining means after a predetermined but variable period to permit return of the shearing elements to operative relation.

6. In a cloth shearing machine embracing separable shearing elements, the combination of seam-energized mechanism for opening the shearing elements, said mechanism being immediately returnable to position for further operation by a second energizing seam while the shearing elements remain open, timer controlled means cooperatively associated with said opening mechanism to permit later return of the shearing elements to operative relationship, said timer being restorable to initial starting position before permitting the return of the shearing elements to operative position by another actuating movement of the opening mechanism.

7. In a cloth shearing machine embracing separable shearing elements, the combination of seam-energized shear-opening mechanism returnable immediately after its actuating movement to position for another opening movement while the shearing elements remain open, timer mechanism operating after a predetermined period of movement to permit return of the shearing elements to operative relation, said timing mechanism being returnable to initial position before completing its normal predetermined movement by an intervening seam induced activation of the shear-opening mechanism.

8. In a cloth shearing machine embracing separable shearing elements, the combination of mechanism for opening the shearing elements for the passage of a seam, timer means for controlling the return of the shearing elements to operative relation after a predetermined movement of the timer from its starting position, and means operable by said shear-opening mechanism for returning the timer toward its initial position before the timer has completed its normal timing movement in order to prolong the open period of the shearing elements.

9. In a shearing machine embracing separable shearing elements, the combination of cloth-energized mechanism for opening the shearing

elements and timer means for keeping them open for a predetermined but variable period before restoring them to closed relation, and means operable by the shear-opening mechanism for prolonging the movement of the timer to allow further time to permit the passage of a succession of protuberances on the cloth.

10. A feeler mechanism for controlling operation of a cloth finishing machine embracing a plurality of feeler fingers arranged to form contact with protuberances on the cloth, the fingers being arranged in spaced, laterally off-set relation transversely of the cloth, one or more of said fingers acting when not moved by engaging protuberances on the cloth to prevent actuation of the feeler mechanism by another feeler finger whose movement effects control of the cloth finishing operation.

11. The combination with shear-opening mechanism of a cloth shearing machine, of an associated energizing selective feeler mechanism embracing plural feeler fingers located in position to be moved by protuberances on the cloth to energize said shear-opening mechanism, said fingers being laterally offset transversely of the cloth, and independently movable by bunches on the cloth that come into engagement with individual fingers, said fingers being interrelated to prevent energizing the shear-opening mechanism by movement of less than the whole series of fingers.

12. A selective feeler mechanism for controlling mechanism for opening shearing elements of a cloth shearing machine embracing a plurality of independently movable feeler fingers arranged in laterally offset relation for engagement with, and movement by, protuberances on the cloth that are approaching in alignment with the respective fingers, one or more of said fingers being arranged in advance of others, each of said advance feelers acting when not moved by a protuberance on the cloth to prevent action of a rear feeler and through the inaction of the rear feeler avoiding operation of the shear opening means.

13. A selective feeler mechanism for controlling mechanism for opening shearing elements of a cloth shearing machine embracing plural feeler fingers arranged in laterally offset spaced relation transversely of the cloth, one or more of them being arranged in advance of the other, each feeler being independently movable by engagement with an aligned protuberance on the cloth passing by, the rearward feeler being correlated with the shear opening mechanism to control its action when moved to active position by engagement with a protuberance on the cloth, but remaining inactive when the advance feeler or feelers are not actuated by a protuberance on the cloth.

14. A seam-actuated mechanism for a cloth shearing machine embracing a plurality of laterally spaced fingers each independently yieldable when engaged by a protuberance on the passing cloth, said fingers being collectively yieldable when engaged by a seam extending across the width of the cloth, and a detent associated with one of said fingers releasable only through the collective action of all the fingers to permit operation of seam-protecting means and thereby preventing injury to the seamed ends of the cloth passing said shearing elements.

15. A selective feeler mechanism for a cloth shearing machine associated with means for protecting against injury a seam passing the shearing elements embracing a controlling member associated with the seam-protecting means and ac-

tuated through the medium of a seam approaching the shearing elements to cause the action of the seam-protecting means, and one or more associated feeler fingers that are individually 5 yieldable when engaged by relatively narrow projections of the travelling cloth and acting when not so engaged to prevent operation of said controller member.

16. A selective feeler mechanism for a cloth 10 shearing machine embracing one or more fingers arranged to present plural spaced contact points for engagement with relatively narrow protuberances of the cloth, the finger being mounted to permit either individual contact point to yield in 15 the direction of the travel of the cloth when it is engaged by a protuberance of the passing cloth without actuating the finger, said finger being movable as a whole when all contact points are simultaneously so engaged and acting by such 20 movement to cause energizing of seam-protecting means.

17. A seam-protecting means for a cloth shearing machine embracing a constantly rotated driver, two pinions loosely related to said driver 25 and arranged in coaxial alignment therewith, each pinion being arrestable to cause rotation of the other in a direction opposite to the rotation of the driver, one of said pinions being momentarily arrested through the medium of seam-controlled means and the other being connected with means for operating a seam-protecting means to prevent injury to the seam passing the shearing line and being immediately returnable to repeat position as soon as it has actuated the 35 seam-protecting means.

18. Seam-protecting means for a cloth shearing machine combined with seam-controlled mechanism for operating it which embraces a continuously rotating driver, pinions loosely and 40 coaxially related to said driver, seam-controlled means for arresting the rotation of one of said pinions and thereby cause reverse rotation of the other pinion in relation to the rotation of the driver, such reversely rotated pinion acting to 45 cause operation of the seam-protecting means and being immediately restored to position in readiness for another seam-protection operation as soon as the seam-controlled pinion is released from arrest of its movement.

50 19. Mechanism for opening the shearing elements of a cloth shearing machine to allow the passage of a seam without injury embracing two loosely mounted interacting revolvable pinions, and a constantly rotatable driver all in coaxial alignment, a seam-controlled member for momentarily arresting rotation of one pinion, thereby producing rotation of the other reverse to the rotation of the driver, means for opening the shearing elements rendered active by the reverse 55 rotation of the second pinion, said opening mechanism being returned to repeat position upon the release of the seam-controlled pinion, and means for retarding the return of the shear opening mechanism through the medium of the seam-controlled pinion.

20. Mechanism for opening the shearing elements of a cloth shearing machine to permit passage of a seam embracing two loosely mounted revolvable pinions coaxially associated with a continuously 70 rotating driver, seam-controlled means for momentarily arresting the rotation of one pinion and thereby causing reverse rotation of the other pinion opposite to the driver rotation through an epicyclic gear element intermeshing 75 with the first-mentioned pinions, the said shear

opening pinion being instantly returnable to position to repeat its operation as soon as it has opened the shearing elements.

21. The combination with seam-controlled mechanism for opening the shearing elements of a cloth shearing machine, said opening mechanism being immediately returnable to position to repeat after the completion of said opening, the shearing elements being retained in open position a predetermined but variable period, and 10 a timer mechanism for controlling the return of the shearing elements to operative relation, said timer mechanism embracing a member movable back to starting position when the shearing elements are opened and movable forward to releasing position to effect closing of the shearing elements and being returnable to initial position at any stage of its movement by another operation of the shear opening mechanism.

22. In a shearing machine having separable 20 shearing elements, the combination with seam-energized mechanism for opening the shearing elements for the passage of a seam, said seam-energized mechanism being immediately returnable to repeat its operation, means for retaining 25 the shearing elements in open position for a predetermined time, a timed release member movable through a predetermined but variable arc of movement to release said retaining means and permit the return of the shearing elements 30 to closed relation, a continuously rotating ratchet for controlling the release movement of said member while permitting said member to return to initial position at any stage of its movement.

23. In a cloth feeler mechanism for the control 35 of a cloth finishing machine, the combination with a movable feeler of calibrating members engaging opposite faces of the cloth passing between them, one of them being capable of limited yielding movement in proportion to the 40 thickness of the body of the cloth passing between, the advance portion of the yielding calibrator being disposed opposite the feeler and in seam-engaging proximity thereto and being movable away from the feeler in accordance with the 45 extra thickness of the cloth to allow such cloth to pass through without actuating the feeler while keeping such advance portion of the calibrator sufficiently near the feeler to insure engagement and movement of the feeler by a cloth- 50 seam.

24. In a feeler mechanism for controlling operation of a cloth finishing machine, the combination with a seam-engaging feeler positioned to be engaged and moved by a seam in the cloth, 55 calibrating members embracing a fixed axis roller engaging one face of the cloth beyond the feeler and on the same side of the cloth, a pivotal bracket carrying a calibrating roller in opposition to said first-mentioned roller to press the 60 body of the cloth, said bracket extending to a point opposite the feeler and being swingable away from the feeler means for yieldingly retaining the bracket in proximity to the feeler to engage a cloth-seam with the feeler to actuate it 65 while at the same time permitting cloth of extra thickness to pass through without operating the feeler.

25. In a feeler mechanism for controlling action of a cloth shearing machine or the like, 70 the combination with a feeler finger arranged to be engaged and actuated by a seam across the cloth passing by, calibrating means engaging the interposed cloth travelling by the feeler to adjust itself to allow different thicknesses of cloth 75

to pass by without operating the feeler while insuring engagement of a seam with the feeler to effect operation of the feeler.

26. In a shearing operating control device for a cloth shearing machine, the combination of a detector arranged so that a portion of the cloth above normal thickness will swing the detector, means whereby the shearing of the cloth will be

interrupted when the detector so swings, and means whereby, if a second abnormal thickness of the cloth passes, before the complete cycle of the interruption is completed, the cycle of interruption will be prolonged.

CHARLES G. RICHARDSON.
JOHN W. HOGUE.
